UNITED STATES PATENT OFFICE.

TOMOZO NOSE, OF TOYAMA-KEN, JAPAN.

LOTTING MACHINE.

Application filed February 25, 1927. Serial No. 171,056.

This invention relates to improvements in lotting machines, more particularly to a lotting machine comprising a revolving polygonal container for the lot balls having an inlet orifice for inserting the balls and an outlet orifice for drawing out the same, there being a lotting box arranged in the said container, which consists of a base board with a top board and is adapted to successively 5 eject the lot balls from the said container. The invention has for its object to provide a lotting machine, whereby the lot balls in the said container may be drawn out positively one by one at each revolution of the said 10 container without confusion.

In the accompanying drawings:

Fig. 1 is a perspective view of the entire machine.

Fig. 2 is a side view of the machine.

Fig. 3 is a perspective view of the machine, an end plate of the container for the lot balls being removed, to show an inner view thereof.

Fig. 4 is an enlarged perspective view of 20 the lotting box.

Fig. 5 is a similar view of the lotting box, the top board being lifted to show an inner view thereof.

Figs. 6^a, 6^b, 6^c and 6^d show four enlarged 30 perspective views of the lotting box, partly in section, to show the conditions in four successive positions at each revolution of the container for the lot balls.

Similar reference numerals in the drawing 35 indicate like parts.

In the lotting machine previously known, it has been proposed to draw out the lots through the complicated means of sliding valves, so that the machine is too complicated for practical use. Another type of lotting machine is designed to allow the lot balls to roll out, opening a shutter suspended in the way of the said lot balls, but this construction allows two or more balls run out at 40 a time. In the present invention these defects are eliminated by the use of a lotting box of novel construction.

Referring to the drawings, the reference 45 numeral 1 designates a container for the lot balls, the container being polygonal in its general outline and provided with an inlet orifice 2 for inserting the lot balls. It is also provided with an outlet orifice 3 for ejecting the balls. Secured to the container 1 is a 50 shaft 4 which is provided with a crank 5 at the one end, on one arm of which is mounted

a handle 6. The container 1 is rotatably mounted on standards 7 and 8 secured on a base plate 9. On the base plate 9, an enclosure 10 having a neck 11 is arranged, the 60 larger compartment 12 of which serves for receiving the lot balls coming from the outlet orifice 3 of the container 1 and the smaller compartment 13 serves for the 65 inspected lot balls.

In the container 1, a lotting box 14 is secured to one of the sides, said box having an outlet orifice 3 for the lot balls, as shown in Fig. 3. The lotting box 14 consists of a rectangular base board 15 and a top board 16. 70 The base board 15 is provided with grooves 17 and 18, the latter being longer than the former. Adjacent the closed end of the groove 17, an outlet orifice 19 is provided. The wall of the closed end of the groove 18 is inclined. A blocking strip 20 is diagonally secured to the base board 15, near the open ends of the grooves 17 and 18, to obstruct said grooves. The groove 17 communicates with the groove 18 through a transverse groove 21 adjacent the inside of the blocking strip 20. A swinging shutter 22 consisting of right-angled two wings 23 and 24 is hinged on a pivot pin 25 in the groove 18. The top board 16 is provided with a cavity 26 to provide a space for the swing of the shutter 22 and a curved groove 27 to provide a passage for the lot balls rolling from the groove 18 into the groove 17 when the lotting box 14 is turned upside down, and is 80 also cut away in one side adjacent the closed end of the grooves 17 and 18 on the base board 15 to provide a guide way 28 having an inclined side wall 29 and a vertical side wall 30 for guiding the lot balls in the container 1 into the groove 18 on the base board 15 (Figs. 4 and 5).

In operation, many lot balls are put into the container 1 through the inlet orifice 2, and the inlet orifice is closed by suitable 100 means. The container 1 holding the lot balls is rotated in a counter clockwise direction by means of the handle 6 so that the lot balls become thoroughly mixed. During this operation, the lot balls leave the container, as the container is rotating in such direction that the lot balls follow the guide way 28 in the top board 16 of the lotting box 14, the slanted end of the groove 18 serving for inlet orifice of the lot balls. After the lot balls 110 in the container 1 have been mixed, the container 1 is rotated in the reverse direction by

means of the handle 6. In this operation, when the lotting box 14 is in the position A as shown in Figure 6 the lot balls are scooped up by the guide way 28 and roll into the 5 groove 18, rolling along the inclined side wall 29 of the said guide way. In the position B, in which the container 1 has been rotated through an angle of 90°, the lotting box 14 contains only one lot ball in the 10 groove 18. The lot ball then rolls down on the blocking strip 20 in the said groove by swinging the shutter 22 through angle of 90°, the shutter preventing another ball from rolling into the inner side of the groove 18, a 15 wing 23 of the said shutter abutting the bottom of the groove and another wing 24 obstructing the groove. In the position C, in which the container has been rotated further through an angle of 90°, the shutter 22 20 hangs on its pivot pin 25 and the lot ball rolls from the groove 18 into the groove 17 through the grooves 21 and 27 in the top board 16. In the position D in which the container has been rotated further through 25 an angle of 90°, the shutter returns to the first position and the lot ball rolls down into the outlet orifice 19 through the groove 17. When the container has been rotated further to the first position A, the lot ball 30 rolls down in the lot ball room 12 on the base plate 9 through the outlet orifice 3 in the container 1. Thus the lot balls are to be drawn out one by one at each revolution of the container.

35 Having now particularly described and ascertained the nature of my invention and in what manner the same is to be performed, I declare that what I claim is:

1. A lotting machine, comprising a polygonal revolving container for lot balls, a 40 lotting box secured to said container, said lotting box consisting of a base board provided with grooves for passage of the lot balls, a swinging shutter hinged in one of said grooves, and a top board provided with 45 a guide way and a groove for the passage of the lot balls, the grooves in the base board being so formed that the lot balls are permitted to enter said box when the container is rotated in one direction and prevented 50 from entering said box when the container is rotated in the opposite direction.

2. A lotting machine, comprising a polygonal revolving container for lot balls having an inlet orifice and an outlet orifice for 55 the lot balls, a lotting box secured to said container, said lotting box consisting of a base board provided with two grooves communicating with each other through a transverse groove for the passage of the lot balls, 60 one of said grooves being provided with an outlet orifice for the lot balls and the other with a swinging shutter consisting of two right-angled wings, hinged on a pivot pin in the bottom of said groove, and a top 65 board provided with a guide way having a vertical wall and a slanted side wall and a groove for the passage of the lot balls, whereby the lot balls are permitted to enter said box when the container is rotated in 70 one direction and prevented from entering said box when the container is rotated in the opposite direction.

In testimony whereof I affix my signature.

TOMOZO NOSE.
